US00D894781S

(12) **United States Design Patent** (10) Patent No.: **US D894,781 S**
Zhang (45) Date of Patent: ** Sep. 1, 2020

(54) **WATCH BAND**

(71) Applicant: **SHENZHEN YOUTIMATE TECHNOLOGY CO., LTD.**, Shenzhen (CN)

(72) Inventor: **Huan Zhang**, Xiangyang (CN)

(73) Assignee: **SHENZHEN YOUTIMATE TECHNOLOGY CO., LTD.**, Shenzhen (CN)

(**) Term: **15 Years**

(21) Appl. No.: **29/726,352**

(22) Filed: **Mar. 3, 2020**

(51) LOC (12) Cl. **11-01**

(52) U.S. Cl. **D11/13**
